UNITED STATES PATENT OFFICE.

RALPH G. TAYLOR, OF DAVENPORT, IOWA, ASSIGNOR, BY MESNE ASSIGNMENTS, TO THE BETTENDORF COMPANY, OF BETTENDORF, IOWA, A CORPORATION OF IOWA.

OPERATING MECHANISM FOR DUMP-DOOR WINDING-SHAFTS.

1,104,393.

Specification of Letters Patent.

Patented July 21, 1914.

Application filed April 4, 1912. Serial No. 688,482.

To all whom it may concern:

Be it known that I, RALPH G. TAYLOR, a citizen of the United States of America, and resident of Davenport, Scott county, Iowa, have invented a certain new and useful Improvement in Operating Mechanism for Dump-Door Winding-Shafts, of which the following is a specification.

My invention relates to improvements in door operating mechanism for dump cars and particularly to that type of mechanism as shown in my copending applications Serial No. 658000 filed Nov. 1st, 1911 and Serial No. 680614 filed Feb. 29th, 1912, in which a creeping winding shaft is employed, having either a vertical or lateral movement relative to the car-body; and its principal object is to maintain the operating ratchet, the ratchet pawl and the pawl locking dog in fixed relation one to the other regardless of the position of the winding shaft in its creeping movement. This I accomplish by the mechanism illustrated in the accompanying drawings, in which—

Figure 1 is a side elevation of the end of a body bolster of a dump car, showing my device in place. Fig. 2 is a preferred form of ratchet pawl. Fig. 3 is the pawl plate in perspective. Figs. 4, 5 and 6 are parts of the operating mechanism. Fig. 7 is the body bolster bracket in perspective. Fig. 8 is a plan view of the operating device. Fig. 9 is a side elevation of my device as applied to the underside of a side dump hopper. Figs. 10 and 11 are the preferred form of pawl and locking dog shown in Fig. 9. Fig. 12 is a perspective of pawl plate shown in Fig. 9. Fig. 13 is a sectional view taken on line A—B of Fig. 1.

Similar numerals refer to similar parts throughout the several views.

To the end of the body bolster 2, which carries the floor sheet 3 in the usual manner, is securely riveted the shaft bracket 5, and the car stake 4 riveted to the outer face thereof in the usual manner.

The square end of the winding shaft 6 extends sufficiently through slotted opening in bracket 5 to accommodate ratchet 7 which is provided with a square opening to snugly fit the shaft. Next to the outer face of and loosely sleeved over the extending hub of the ratchet is the operating lever socket 8, being held in place by the washer 15 which is pinned to the end of the shaft. Next to the

inner face of the ratchet, between it and the bracket 5, is the pawl plate 9, which slidely engages pintle 5^a, extending from bracket 5 through the slotted opening 12 and also engages the hub portion 14 of ratchet 7 through the circular opening 13. It is thus to be seen, when the ratchet is rotated by lever socket 8 (and pawl not shown) and moves laterally with the shaft it will swing the pawl plate about the pintle 5^a; and as ratchet pawl 11 is pivotally mounted on pintle 10 which is integral with the pawl plate 9, it also must move with the pawl plate, maintaining its operative position with the ratchet regardless of the location of the ratchet in the slotted opening 16 of bracket 5 during the creeping movement of the shaft.

Fig. 1 shows my improved device as applied to a creeping shaft having lateral movement relative to the car body, while Fig. 9 shows the device applied to a shaft having vertical movement. In the latter construction the bracket 17 is secured to the underside of a hopper slope sheet or other convenient place on car body and provided with a large vertical opening in which shaft 6 is vertically movable. Bracket 17 is also provided with the integral pintle 17^a about which pawl plate 9 is made to swing through the slotted opening 12. Opening 13 engages the hub of ratchet 7. Thus as ratchet and shaft move vertically the pawl plate must swing also, carrying with it ratchet pawl 18 and locking dog 19, which are pivotally mounted on pintles 10 and 20, thereby keeping pawl and dog in fixed relation to the ratchet 7 regardless of its position in its up and down travel.

What I claim as my invention is—

1. In combination a winding shaft bracket provided with a pintle extending laterally therefrom, a winding shaft and ratchet, a pawl plate journaled on said ratchet and slidely engaging said pintle.

2. In combination a winding shaft bracket provided with a slotted opening, a winding shaft adapted to travel in said opening, a ratchet adapted to rotate said shaft, a pawl plate swingingly attached to said bracket and actuated by said shaft substantially as described.

3. A movably supported winding shaft, a ratchet secured to said shaft and provided with extending hub portions, a pawl plate

2
swingingly mounted on said ratchet hub extension, a ratchet pawl and locking dog carried by said pawl plate.

4. A winding shaft operating mechanism comprising a ratchet secured to a movably supported shaft, means to rotate said ratchet, a swingingly mounted pawl plate journaled on said shaft, a pawl and locking dog pivotally secured to said pawl plate

and means to maintain same in fixed relation to said movable shaft. ¹⁰

Signed by me at Davenport Iowa this 1st day of April 1912.

RALPH G. TAYLOR.
